FIG. 1.

FIG. 2.

FIG. 3.

Horace Williams
INVENTOR
by *Att. H. Williams*
his Attorney

UNITED STATES PATENT OFFICE.

HORACE WILLIAMS, OF ST. PETERS, SOUTH AUSTRALIA, AUSTRALIA.

DIRECTION INDICATOR.

Application filed August 31, 1928, Serial No. 303,229, and in Australia September 20, 1927.

My invention relates to an improved signalling device principally for use in connection with closed motor vehicles, the object of the same being to provide means whereby the 5 occupant of a closed car or other vehicle can conveniently signal his intention to turn a corner or execute other movements if so desired.

This device consists of an arrow head or 10 other distinguishing figure which is mounted upon an expanding lattice supported from a fixed portion of a car and provided with means for operating the same.

My invention will be readily understood 15 when described by aid of the accompanying illustrative drawings wherein:—

Fig. 1 is a side elevation of the device extended to full length to display the signal.

Fig. 2 is a side elevation of the same device on larger scale but with signal arm folded.

Fig. 3 is a plan of Fig. 2.

In each of the illustrations similar letters of reference are used to denote similar or 25 corresponding parts wherever they occur.

In the drawings *a* is a fixed portion of the car as for instance a door pillar through which a hole is drilled for the accommodation of a tubular guide *b* upon the end of which 30 there is an enlargement *b'* and a washer may be inserted between the enlargement and the door pillar.

The opposite end of the tubular guide is screw threaded at *b* and supports the clamping nut and washer *c*. Within this tubular guide I support a slide rod *d*, furnished at its 35 inner end with a press button or stud *e*. The opposite end of the rod terminates with a block *e'* which pivotally supports the centre portion or first extension joint of an expandable lattice *f*, the first stationary radial joint being pinned to the enlarged end or fixed block *b'* of the tubular guide *b* by a pin or rivet *g*. The block *e'* also supports a spring 40 clip *b*.

The succeeding arms of the expandable lattice lie parallel to each other in two rows when folded as in Figs. 2 and 3, but are extended as in Fig. 1 by the operation of the 45 slide rod *d* as will be well understood upon reference to the drawings.

The two outermost members of the lattice each support, by means of rivets *f'*, plates of

metal *h* and *h'* preferably cut to the form of a triangle with the apex removed. When the 55 arms of the lattice are extended as in Fig. 1 the plates *h* and *h'* will appear in the form of an arrow head, but when the lattice is folded the plates *h* and *h'* will be respectively accommodated under and over the arm *f* as 60 illustrated in Fig. 2.

In applying my invention to practical use the device is fitted to a fixed part of the car in the manner indicated and in a position convenient to the driver, so that when he desired 65 to turn a corner he can give the necessary signal by pressing the button with his hand or elbow to extend the lattice and arrow, the spindle being withdrawn when the turning evolution has been completed, and the lattice 70 is held by the clip.

What I claim is:—

1. In an improved signalling device wherein an expanding lattice mechanism for operating the signalling device is used, metal plates attached to the opposite sides of the outer members of the lattice, said plates being mounted so as to form an arrow head when the lattice is extended and to fold respectively under and over opposite sides of the lattice when 80 said lattice is contracted, longitudinally embracing the sides of said lattice.

2. In a signalling device for motor vehicles, a tubular guide passing through the wall of the vehicle, an enlarged outer head on said guide, an expandable lattice having its inner end attached to said head, a rod passing through said guide, operable from the interior of the vehicle and adapted to extend said lattice, and a spring clip extending from said 85 head and embracing said lattice in its contracted position to hold the same in place.

3. In a signalling device for motor vehicles, a tubular guide passing through the wall of the vehicle, an enlarged outer head on said 90 guide, an expandable lattice having its inner end attached to said head, a rod passing through said guide, operable from the interior of the vehicle and adapted to extend said lattice, a spring clip extending from said head 95 and embracing said lattice in its contracted position to hold the same in place, and metal plates attached to the opposite sides of the outer members of said lattice, said plates being adapted to form an arrow when the lattice 100 is extended and to embrace the lattice

longitudinally on either side when said lattice is contracted.

4. In a signalling device of the expandable lattice type, a spring clip rigidly mounted on the lattice support and adapted to hold said lattice in contracted position.

5. In a signalling device of the expandable

lattice type, a spring clip mounted on the lattice support, said clip being longer than the contracted length of said lattice and having a bent-in end adapted to hold said lattice in contracted position. ¹⁰

In testimony whereof I affix my signature,

HORACE WILLIAMS.
